US010493349B2

(12) **United States Patent**
Watterson

(10) **Patent No.:** **US 10,493,349 B2**
(b4) **Date of Patent:** **Dec. 3, 2019**

(54) **DISPLAY ON EXERCISE DEVICE**

(71) Applicant: **ICON Health & Fitness, Inc.**, Logan, UT (US)

(72) Inventor: **Eric S. Watterson**, Logan, UT (US)

(73) Assignee: **ICON Health & Fitness, Inc.**, Logan, UT (US)

(*) Notice: Subject to any disclaimer, the term of this patent is extended or adjusted under 35 U.S.C. 154(b) by 44 days.

(21) Appl. No.: **15/461,119**

(22) Filed: **Mar. 16, 2017**

(65) **Prior Publication Data**

US 2017/0266532 A1 Sep. 21, 2017

DISPLAY ON EXERCISE DEVICE

RELATED APPLICATIONS

This application claims priority to U.S. Patent Application Ser. No. 62/310,659 titled "Display on Exercise Device" and filed on Mar. 18, 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user uses an aerobic exercise machine to have an aerobic workout indoors. One type of aerobic exercise machine is a treadmill, which is a machine that has a running deck attached to a support frame. The running deck can support the weight of a person using the machine. The running deck incorporates a tread belt that is driven by a motor. A user can run or walk in place on the tread belt by running or walking at the tread belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical machines, rowing machines, stepper machines, and stationary bikes to name a few.

One type of treadmill is disclosed in U.S. Patent Publication No. 2009/0209393 issued to Bradley A. Crater. In this reference, a simulated display of a treadmill's console is described. According to one embodiment, the console displays a visual representation of the course over which the user is running. The course may be displayed with video footage that corresponds to the user's location on the course, by using still pictures, or by using computer-generated simulations of the course. For example, a video display of the course could assist a marathon runner who is preparing for the Boston Marathon. By seeing a visual representation of the course, a runner could identify landmarks and aid stations that would assist him in feeling comfortable in running the actual race being simulated at a future date.

SUMMARY

In one embodiment, an exercise device includes a frame, a movable engagement surface connected to the frame and movable in the performance of an exercise, and a display located adjacent to or below at least a portion of the movable engagement surface.

The exercise device may include an exercise deck where the exercise deck includes a first pulley connected to a front

2

portion of the deck, and a second pulley connected to a rear portion of the deck. The movable engagement surface may be a tread belt that surrounds the first pulley and the second pulley.

5 The tread belt may surround at least one region of the display.

The exercise device may include at least a second region of the display that is adjacent to and aligned with the tread belt.

10 The display may be incorporated into the deck.

The display may be aligned with an orientation of the exercise deck.

The tread belt may be a perforated tread belt and the display is visible through the perforated tread belt as the 15 perforated tread belt moves.

The exercise device may include an upright portion of the frame, and a console connected to the upright portion.

The exercise device may include a second display incorporated into the console.

20 The images depicted in the display and the second display may be coordinated.

The movable engagement surface may be a tread belt.

The movable engagement surface may be a foot pedal.

The exercise device may be a rowing machine.

The exercise device may be a stationary bicycle.

25 The display may be covered with a transparent plastic film.

In one embodiment, an exercise device includes a frame, a movable element connected to the frame and movable in the 30 performance of an exercise, and an exercise deck. The exercise deck includes a first pulley connected to a front portion of the deck, a second pulley connected to a rear portion of the deck, and a tread belt surrounding the first pulley and the second pulley. The exercise device further 35 includes a display is incorporated into the deck adjacent to the tread belt.

The tread belt may surround at least one region of the display.

40 The tread belt may be a perforated tread belt and the display is visible through the perforated tread belt as the 45 perforated tread belt moves.

The exercise device may include an upright portion of the frame, a console connected to the upright portion of the frame, and a second display incorporated into the console.

50 In one embodiment, an exercise device includes a frame, an upright portion of the frame, a console connected to the upright portion of the frame, a movable engagement surface connected to the frame and movable in the performance of an exercise, and an exercise deck. The exercise deck includes a first pulley connected to a front portion of the deck, a second pulley connected to a rear portion of the deck, and a 55 perforated tread belt surrounding the first pulley and the second pulley. The display is incorporated into the deck, and the perforated tread belt surrounds at least one region of the display. The display is visible through the perforated tread belt as the perforated tread belt moves. A second display is incorporated into the console and images depicted in the display and the second display are coordinated.

60 BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

65 FIG. 1 illustrates a perspective view of an example of a treadmill in accordance with the present disclosure.

FIG. 2 illustrates a perspective diagram of an example of a tread belt in accordance with the present disclosure.

FIG. 3 illustrates a top view of an example of a display incorporated into a treadmill deck in accordance with the present disclosure.

FIG. 4 illustrates a top view of an example of a display incorporated into a treadmill deck in accordance with the present disclosure.

FIG. 5 illustrates a top view of an example of a display incorporated into an elliptical trainer in accordance with the present disclosure.

FIG. 6 illustrates a top view of an example of a display incorporated into a stationary bicycle in accordance with the present disclosure.

FIG. 7 illustrates a top view of an example of a display incorporated into a rowing machine in accordance with the present disclosure.

Throughout the drawings, identical reference numbers designate similar, but not necessarily identical, elements.

DETAILED DESCRIPTION

For purposes of this disclosure, the term “aligned” means parallel, substantially parallel, or forming an angle of less than 35.0 degrees. For purposes of this disclosure, the term “transverse” means perpendicular, substantially perpendicular, or forming an angle between 55.0 and 125.0 degrees. Also, for purposes of this disclosure, the term “length” means the longest dimension of an object. Also, for purposes of this disclosure, the term “width” means the dimension of an object from side to side. For the purposes of this disclosure, the term “above” generally means superjacent, substantially superjacent, or higher than another object although not directly overlying the object. Further, for purposes of this disclosure, the term “mechanical communication” generally refers to components being in direct physical contact with each other or being in indirect physical contact with each other where movement of one component affect the position of the other.

Additionally, for purposes of this disclosure, the term “user space” means the portion of an exercise device where a user is intended to be located when performing an exercise. Similarly, the term “engagement surface” in the context of the present application means the surface of an exercise device where a user contacts the device and imparts a force. By way of clarification, in the context of a treadmill having a tread belt, the engagement surface of the treadmill is the top surface of the tread belt when it is on the top of the deck and able to be engaged by a user, but not when the tread belt has rotated below the deck.

Particularly, with reference to the figures, FIG. 1 illustrates a perspective view of an example of a treadmill 100. In this example, the treadmill 100 includes an exercise deck 102 and an upright structure 104. The upright structure 104 includes a first post 106 and a second post 108. The first post 106 and the second post 108 support a console 110. A display 112 is incorporated into the console 110.

The exercise deck 102 includes a platform. A first pulley (not shown) is incorporated into a front portion 114 of the exercise deck 102, and a second pulley (not shown) is connected to a rear portion 116 of the exercise deck 102 opposite the first pulley. A tread belt 118 surrounds the first pulley and the second pulley. In the example of FIG. 1, the first and second pulleys are obscured from view underneath portions of a top surface of the platform. The platform may have a length along its longest dimension and a width that is transverse the length.

A display screen 120 is integrated into the platform or deck. This display screen 120 may be used to present information associated with the workout, with the user, with local news, with other types of information, or combinations thereof. In some cases, the deck display screen is controlled through the console, a remote device, or an input mechanism incorporated into the deck. The display screen 120 may also be surrounded by the tread belt 118. Thus, at least a portion of the display may be obscured from view by the tread belt. In some cases, the display screen 120 is wider than the tread belt 118. In this situation, the display screen 120 includes a first portion 122 adjacent a first edge 124 of the tread belt 118 that is unobscured from view, and a second portion 126 adjacent a first edge 128 of the tread belt 118 that is unobscured from view. In this example, the display screen 120 is subjacent a portion of the tread belt’s inside surface.

FIG. 2 depicts a detailed view of an example of a tread belt 200 forming an engagement surface for the user (when above the deck) defining the lower limit of the user space. In this example, the tread belt 200 includes multiple perforations 202. A display screen 204 is incorporated into the deck 206 behind the engagement surface and below the user space relative to the ground, and the display screen 204 is viewable through the perforations 202 of the engagement surface. While this example depicts the perforations 202 as having circular cross sections, the perforations 202 may have any appropriate type of shape including square, slots, triangular, asymmetric, another type of shape or pattern, or combinations thereof.

FIG. 3 depicts an example of a treadmill 300. In this example, a tread belt 302 is incorporated into the deck 304, and the tread belt 302 is solid and opaque. A first display 306 is integrated into the deck 304 lengthwise adjacent to a first edge 308 of the tread belt 302, and a second display 310 is integrated into the deck 304 lengthwise adjacent to a second edge 312 of the tread belt 302. Both the first display 306 and the second display 310 are disposed below the user space and below the engagement surface, between the engagement surface and the ground.

FIG. 4 depicts an example of a treadmill 400. In this example, a display 402 is incorporated into the exercise deck 404. The treadmill 400 also includes an upright structure 406. But, in this example, the upright structure 406 includes a desk 408 and no display screen.

FIG. 5 depicts an example of an elliptical trainer 500. The elliptical trainer 500 includes a frame 502 attached to a base 504. The frame 502 includes a first post 508 and a second post 510. An upright console 512 is connected to the first and second posts 508, 510. The first frame post 508 incorporates a first flywheel 514, and the second frame post 510 incorporates a second flywheel 516. The first flywheel 514 is connected to a first pedal assembly 518 through a crank assembly 520, and the second flywheel 516 is connected to a second pedal assembly 522 through the crank assembly 520.

The crank assembly 520 includes a first crank arm connected to the first flywheel 514 and a second crank arm connected to the second flywheel 516. Each of the first crank arm and the second crank arm include a roller that supports the weight of the pedal assemblies 518, 522 and a user standing thereon.

Each of the first pedal assembly 518 and the second pedal assembly 522 includes a pedal beam, and a pedal is connected to the pedal beam. The pedal may include a gripping surface to grip a user’s shoe as a user executes an exercise with the elliptical trainer 500. The pedal may be bolted or

otherwise fastened to the pedal beam. The pedal defines the engagement surface and the lower surface of the user space.

A front end of the pedal beam of the first pedal assembly 518 is connected to a first arm lever 552 that connects to the frame 502 at a first pivot connection. The first pivot connection is also attached to a first handle section 556 which is accessible to the user as the user is performing an exercise with the elliptical trainer 500. The pedal beam of the second pedal assembly 522 is connected to a second arm lever 560 that connects to the frame 502 at a second pivot connection. The second pivot connection is also attached to a second handle section 564 which is also accessible to the user as the user is performing an exercise with the elliptical trainer 500. As the pedal beams move, the first and second handle sections 556, 564 move accordingly.

The console 512 may contain a display and controls. The controls may allow the user to specify a resistance level to be applied by the resistance mechanism, such as the first and second flywheels 514, 516. In some examples, the controls may also be used to control other operating parameters of the exercise machine, such as incline, side to side tilt, resistance, speaker volume, programmed exercise routines, other parameters, or combinations thereof. The display may show selected parameters to the user. Additionally, the display may be capable of presenting the user's physiological parameters, timers, clocks, scenery, routes, entertainment, other types of information, or combinations thereof.

Further, a display 570 is incorporated into the base 504 below the pedals under the user space relative to the ground and behind the engagement surface. In this example, the display 570 is below the pedals assemblies 518, 522, the crank assembly 520, and the flywheels 514, 516. As the user exercises on the elliptical trainer 500, the user can view portions of simulated scenery and/or other types of information presented in the base's display 570. While this example has been described with two display screens, in other examples, the elliptical trainer includes just a single display screen that is incorporated into the exercise machine's base, located beneath the crank assembly and/or located beneath the upright portion.

FIG. 6 depicts an example of a stationary bicycle 600. In this example, the stationary bicycle 600 includes a frame 602 and a crank assembly 604 attached to the frame 602. As shown, the crank assembly defines the engagement surface and the bottom surface of the user space. A seat 606 is also attached to the frame 602 and positioned above the crank assembly 604. The stationary bicycle 600 also includes an upright portion 608, and a console 610 with a first display 612 is attached to the upright portion 608.

A second display 614 is positioned underneath at least a portion of the frame 602. In this example, the second display 614 is attached below the crank assembly 604. While this example has been described with two displays, in some examples, the stationary bicycle includes just a single display located beneath the crank assembly and/or located beneath an upright portion of the stationary bicycle.

FIG. 7 depicts an example of a rowing machine 700. In this example, the rowing machine 700 includes a main frame member 702 supported by rear supports 704 and a front cross member 706. A flywheel 708 is incorporated into a front portion of the rowing machine 700. A pull cable 710 is connected to the flywheel 708 at a first cable end, and a handle 712 is connected to the pull cable 710 at a second cable end. A seat 714 is slidably attached to the main frame member 702 and defines the lower surface of the user space and is an engagement surface.

A first display screen 716 is attached to a console 718 of the rowing machine 700. A second display screen 720 is attached to the rowing machine 700 beneath the main frame member 702, below the user space or behind the engagement surface. In this example, the second display screen 720 is located beneath the resistance mechanism (e.g. the flywheel). While this example is depicted with two displays, in other examples, the rowing machine includes a single display located beneath the main frame member 702.

General Description

In general, the invention disclosed herein may provide an user with an exercise device such as a treadmill that has several advantages over conventional exercise devices or treadmills. The treadmill may include a running deck that has first pulley in a front portion of a platform and a second pulley incorporated into a rear portion of the platform. A tread belt may surround the first and second pulley and, when on the top portion of the running deck, defines the lower portion of the user space and provides an engagement surface. A motor can be attached to either the first or the second pulley so that as the motor rotates its shaft, the connected pulley rotates with the motor causing the tread belt to move.

The platform may have a length along its longest dimension and a width that is transverse the length. The width of the tread belt may span just a portion of the deck's platform. In this circumstance, the deck is wider than the tread belt. Thus, a first portion of the deck may extend past a first side of the tread belt, and a second portion of the deck may extend past a second side of the tread belt.

In some examples, the treadmill may include an upright structure. The deck may be connected to the upright structure so that the upright structure's vertical orientation is transverse the deck's horizontal orientation. An incline mechanism may be incorporated into the treadmill so that the deck can change its incline orientation with respect to the upright structure. In some cases, the deck can be oriented at varying inclined orientations, varying declined orientations, or a neutral orientation. Further, in some instances, the treadmill deck may have the capability of being tilted from side to side.

A console may be connected to the upright structure. The console may include a display, an input mechanism, a cooling mechanism, a retention area for holding an object (e.g. mobile device, book, water bottle, etc.), or combinations thereof. The console's display may present various types of information to the user.

The input mechanism provides the user an ability to communicate with the treadmill. For instance, the user may select a tread belt speed, a pre-programmed workout, a climate setting, an incline orientation, a tilt orientation, an entertainment setting, and so forth, with the input mechanisms. The input mechanisms may include a touch screen, a push button, a dial, a lever, a microphone, another type of input mechanism, or combinations thereof.

For example, the console may present physiological information about the user, like the user's heart rate. Also, the console may also present information about a selected programmed workout, the tread belt's speed, the distance traveled by the user, another type of parameter, or combinations thereof. In some cases, the console's display may depict scenery to provide an outdoor feel. In some cases, the orientation of the deck's platform may be synched with the scenery so that the deck mimics the terrain depicted in the display. For example, the platform may be inclined when the

display depicts that the path is going uphill, or the platform may be declined when the display depicts that the path is going downhill.

In some embodiments of the invention, a second display is incorporated into the deck's platform below the user space. This deck display may be positioned under the tread belt or other engagement surface, adjacent to the tread belt, to the side of the tread belt, forward of the tread belt, rearward of the tread belt, or combinations thereof.

The second display may be a digital display. In this circumstance, the display may be in communication with a processor and memory. The memory may store video files that can be depicted in the deck's display. In some circumstances, the video files include scenery content or other types of content. The display may also be in communication with a remote device that streams or downloads the content to the display. In some cases, the deck's display may be used to display information associated with the workout, with the user, with local news, with other types of information, or combinations thereof. In some examples, the treadmill's operational parameters can be presented in the display screen.

Any appropriate type of display may be incorporated into the deck. A non-exhaustive list of display types that may be used in accordance with the principles described in this disclosure, includes cathode ray displays, liquid crystal displays, flat panel displays, stereo displays, plasma displays, electronically modulated optical displays, color display, monochrome displays, touch displays, electroluminescent panels, light emitting diode displays, nano-emissive displays, quantum dot displays, digital light processing displays, active matrix displays, other types of displays, or combinations thereof.

The display screen may be made of any appropriate type of material that can withstand a user standing on it. This material may include Kevlar®, plastic, or another type of material. Further, the display screen may also be covered with a transparent coating that protects the screen from abrasion, dropped objects, or other types of contact.

In one embodiment, the display incorporated into the deck is located subjacent to at least a portion of the tread belt behind the engagement surface. In this circumstance, the tread belt may be perforated or have other types of openings that allow the display to be visible through the tread belt. In another example, at least a portion of the tread belt may be transparent and/or translucent, which allows the user to see at least a portion of the display as the tread belt rotates or the tread belt is not moving with respect to the deck.

In some examples, the display is wider than the tread belt. In this type of example, a first portion of the display extends beyond the edge of the tread belt's first side and a second portion of the display extends beyond the edge of the tread belt's second side. Portions of scenery or other information depicted with the deck's display can be visible on the exposed portions of the display on either side of the tread belt. In this situation, the tread belt surrounds just a portion of the display incorporated into the deck.

In some cases, the deck includes more than one display. A first display may be positioned adjacent to a first edge of the tread belt, and a second display may be positioned adjacent to a second edge of the tread belt. In this situation, the edges of the first and second deck displays terminate before reaching the tread belt. In other words, the tread belt may not overlap with these first and second deck displays. These first and second deck displays may be aligned with the orientation of the deck. In other words, these displays may be situated lengthwise along the deck and/or aligned with

the length of the tread belt. In some examples, at least one of the first and second deck displays span at least 10 percent of the deck's length, at least 20 percent of the deck's length, at least 30 percent of the deck's length, at least 40 percent of the deck's length, at least 50 percent of the deck's length, at least 60 percent of the deck's length, at least 70 percent of the deck's length, at least 80 percent of the deck's length, another percentage of the deck's length, or combinations thereof. In some examples, the deck includes at least one deck display that are just situated on one side of the deck.

The deck display may include a presentation side where the display presents content and is visible to the user. The deck display may also include a back side, which is facing downward and is not visible to the user when the treadmill is in operation. The tread belt includes an outer surface on which the user makes contact during the performance of an exercise, an inner surface which makes contact with the display and pulleys. The inner surface of the tread belt may surround the presentation side of the deck display and also surround the back side of the deck display.

In those situations where the tread belt includes perforations or other types of openings defined in the tread belt, the perforations may be defined in the outer surface and in the inner surface of the tread belt. The perforation may extend from the tread belt's outer surface to the tread belt's inner surface. Thus, the perforations may penetrate through the entire thickness of the tread belt. The perforations may be included along an edge of the tread belt, in the center of the tread belt, along a width of the tread belt, in patterns in the tread belt, arranged in another manner in the tread belt, or combinations thereof.

In other examples, the tread belt includes windows of transparent material. In some cases, the windows include a transparent material that fills the perforations so that the presentation side of the deck's display is visible. By incorporating the windows into the tread belt, the presentation side of the deck's display is protected from dirt, dust, or other types of particles that may reach the display through the perforations. In other examples, the tread belt is made of a material where the entire tread belt is transparent. But, in other examples, just portions of the tread belt are transparent. The windows may be chemically bonded to the walls of the tread belt and include a flexibility and strength compatible loads with which the tread belt experiences. For example, the windows may include a compressive force that can withstand the user's weight or have the flexibility to curve around the pulleys are the windows approach the ends of the deck. In some cases, the windows have a compressive strength is that is less than the compressive strength of the tread belt. In these circumstances, the tread belt is constructed to direct the loads away from the windows. For example, the windows may have a shorter length than the length of the perforations wall. In this example, the top of the window may not come into contact with the user's shoe and the bottom of the window may not come into contact with the display thereby forcing the user's weight to be loaded through the tread belt and not the windows.

The presentation side of the display may have a low friction surface so that the tread belt may slide along the presentation side without a substantial drag. In those examples where the tread belt includes perforations of other types of openings defined in the tread belt, the perforations may include a perforation edge formed between a wall of the perforation and the inner surface of the tread belt. The perforation edge may be constructed to wipe away debris, dirt, dust, excess lubricant, or other substances that may obscure the view of the deck's display. In some cases, the

perforation edge is shaped so that debris or other substances may be caught by the perforation edge, which moves the debris or other substances along with the tread belt and off of the display. In some cases, the inner surface of the tread belt may be lined with a soft material that can collect dust or other types of particles. This lining may be a fabric, a soft material, or another types of material that can collect debris while having a low likelihood of scratching the display.

In examples where the tread belt is constructed to clean the display as the tread belt moves, any appropriate mechanism for cleaning the tread belt may be used. A wiper may be disposed adjacent to an exit side of the display that wipes off the debris or other substances collected in the perforations or the tread belt's inner surface. In other cases, a blower may direct a gas (e.g. air) over the regions of the tread belt's inner surface to remove the debris. In other cases, a chemical may be applied to the inner surface to clean the inner surface as the tread belt moves off of the display. In yet other examples, the inner surface of the tread belt may pass over a magnet to remove debris with magnetic properties from off of the tread belt's inner surface.

In some cases a lubricant is applied between the inner surface of the tread belt and the presentation side of the display screen. In these situations, the lubricant may be a transparent lubricant that maintains the visibility of the display screen.

In yet another example, the deck may include multiple displays. In this type of example, a first deck display may be incorporated into the region of the deck's platform that is adjacent to a first edge of the tread belt, and a second deck display may be incorporated into the region of the deck's platform that is adjacent to a second edge of the tread belt. In examples with two deck display screens, the deck display screens may depict the same images or they may depict different images.

In examples where the console includes sensors that measure the user's physiological information, the physiological information may be transmitted to the deck display through a wireless transmission protocol. In other examples, the display incorporated into the deck may be hardwired to the sensors located in the console.

The treadmill may also be in communication with a remote device over a network, such as the internet. The user may access the records of his or her exercise history, previous workouts, exercise recommendation, personal information, or combinations thereof. The remote device may record the workout information and/or the physiological information associated with the workout. An example of a user program that may be compatible with the principles described herein can be found at www.ifit.com, which is administered through Icon Health and Fitness, Inc. located in Logan, Utah, U.S.A. In other cases, the remote device includes video files or other types of files with others types of information.

The information received from the remote device may be displayed in the console's display, in the deck's display, or combinations thereof. In some examples, all of the information is sent to both the console's display and to the deck's display. In this situation, both the displays in the console and the deck may show the same information. In other examples, the information from the remote device is separated into parts. In this situation, at least a portion of the information can be sent to the console's display and another portion of the information can be sent to the display in the deck. Under these circumstances, the console's display and the deck's display may present different information. Where the console display and the deck display present different information, some of the information depicted in each of the screens may overlap with each other.

In some embodiments, the treadmill simulates an outdoor trail on which the user is exercising. The console's display depicts the type of scenery that a runner would likely see if he or she were running on the simulated outdoor trail. This type of scenery may include the trail ahead of the user, the background scenery, landmarks in the distance, animals, vegetation, other types of scenery, the horizon, and combinations thereof. In some cases, the deck's display screen may depict the same scenery as is depicted in the console's display. In some other examples, the deck's display may depict just a subset of the scenery or different scenery as depicted in the console's display. For example, the scenery depicted in the deck's display may include just the scenery that is likely to be viewed by a user if the user were running on the simulated trail. In this example, the user may see the scenery from a top view in the deck's display whereas the user see the scenery from a side view in the console's display. The top view of the scenery may include the trail, the vegetation around the trail, rocks, landmarks near the trail, just scenery that is close to the running path, other types of scenery, or combinations thereof.

In some circumstances, the console's display screen and the deck's display screen are coordinated. In this situation, the scenery from the console's display may flow to the deck's display as the user progresses along the simulated trail. For example, the console's display may depict a side view of a rock next to the running path, as the user progresses along the trail, the console display presents the rock so that the rock appears to get closer to the user. At some point along the user's progression, the side view of the rock transitions from the off of the console's display screen to the deck screen where the rock is depicted from a top view. While this example describes an image of a rock transitioning from the console's display to the deck's display, images of any other appropriate type of scenery can transition from the console display to the deck display. In some case, the scenery in the deck's display is depicted from a side view as well.

For purposes of this disclosure, the term "coordinated" generally refers to the information depicted in the first display having a relationship with the information depicted in the second display. As illustrated above, the relationship between the information in the first display and the information in the second display is that at least some of the information from the first display transitions to the second display. In this situation, the overlapping information that was presented in the first display is also shown in the second display, but the presentation of the overlapping information in the second display is delayed in time. This is one example of coordination between what is depicted in the first display and what is depicted in the second display. Further, coordinated display screens may include presenting the same information in both screens at the same time. In other examples, coordinating the display screens includes causing the second display screen to be an extension of the first display screen.

In other examples, a relationship between the information depicted in the first and second display screens may be a relationship where the first display screen depicts an overview of a simulated course to be traveled by the user, and the second display depicts scenery of the simulated course. In this situation, the content depicted in the first and second displays convey information about the same course, although the type of content presented in the first and second displays are different.

A splitter may divide portions of a video feed (e.g. from a remote device or internal memory) that sends some of the video data to the console's display while sending other data to the deck's display. In some cases, the splitter may cause the video data to be sent to each of the deck's display and

11

the console's display at the same time. In other situations, the splitter may cause the separated video data to be sent to the deck display at a delayed time from the time that the splitter sends the video information to the console's display. In this case, some of the same scenery may be shown in both the console's display and the deck's display, but the scenery may be depicted in the deck's display at a later time than when the scenery is depicted in the console's display. In yet other examples, the video feed to the console's display and the video feed to the deck's display may be separate and independent video feeds. In this example, the scenery or information depicted in the deck and console displays are different. But, in other examples, the scenery depicted in the deck and console displays may depict the same simulated surroundings even though video feeds are from different, independent files.

While the examples above have been described with reference to a treadmill with a console display and a deck display, the treadmill may include a deck display without the console display. Further, while these principles have been described with respect to a treadmill, a display located below the movable element of the exercise device may be incorporated into other types of exercise machines below the user space under the engagement surface.

For example, a display may be incorporated below the foot pedals in an elliptical trainer or a stationary bicycle. In these examples, the user has the advantage of having a display beneath him or her during the performance of the exercise thereby helping the user feel more like he or she is actually in a virtual setting. Further, the elliptical or stationary bike may present information to the user through the display located beneath his or her feet. In some examples, the top view images of a road or bicycle trail may be depicted in the displays located beneath, proximate, and/or subjacent to the foot pedals. In another example, the display may be incorporated into a rowing machine where the display is located beneath the slidable seat, the resistance mechanism, or another component of the rowing machine that defines the lower surface of the user space or engagement surface. In this example, the display may simulate ocean, river, and/or lake water as though the user were rowing on these bodies of water.

The deck displays, displays incorporated into the base of the elliptical trainer, displays located beneath resistance elements, displays located beneath pedals, displays located beneath rowing mechanisms, or other types of displays described above may include an ability to move. In some cases, these displays may incline, decline, rotate, twist, tilt from side to side, or other types of movement. In some cases, these displays move in response to events occurring in the simulated workout. For example, the displays may incline as the user is simulated to travel up steep portion of an outdoor trail. In cases where the display is a deck display in a treadmill, the deck displays may incline or otherwise move with the deck. But in some cases, the deck display may incline or otherwise move independent of the deck.

What is claimed is:

1. An exercise device, comprising:

a frame;

an exercise deck including:

a top surface;

a first pulley connected to a front portion of the exercise deck;

a second pulley connected to a rear portion of the exercise deck; and

a tread belt surrounding the first pulley and the second pulley and movable in a performance of an exercise;

12

a first deck display incorporated into the top surface of the exercise deck lengthwise adjacent to a first lengthwise edge of the tread belt; and

a second deck display incorporated into the top surface of the exercise deck lengthwise adjacent to a second lengthwise edge of the tread belt.

2. The exercise device of claim 1, further comprising: an upright portion of the frame; and a console connected to the upright portion.

3. The exercise device of claim 2, further including a third console display incorporated into the console.

4. The exercise device of claim 3, wherein images depicted in the first deck display, the second deck display, and the third console display are coordinated.

5. The exercise device of claim 1, wherein the first deck display and the second deck display are coated with a transparent coating that protects the first deck display and the second deck display from abrasion.

6. The exercise device of claim 1, wherein the tread belt does not overlap with the first deck display or the second deck display.

7. The exercise device of claim 1, wherein the first deck display and the second deck display span at least 20 percent of the length of the exercise deck.

8. The exercise device of claim 1, wherein the first deck display and the second deck display span at least 50 percent of the length of the exercise deck.

9. The exercise device of claim 1, wherein the first deck display and the second deck display span at least 80 percent of the length of the exercise deck.

10. The exercise device of claim 1, wherein the first deck display and the second deck display are configured to have different images depicted thereon.

11. The exercise device of claim 1, wherein the first deck display and the second deck display are configured to display information received over the internet by the exercise device from a remote device.

12. The exercise device of claim 1, wherein each of the first deck display and the second deck display is a digital display configured to depict video.

13. An exercise device, comprising:
a frame;
an upright portion of the frame;
a console connected to the upright portion of the frame;
an exercise deck including:

a first pulley connected to a front portion of the exercise deck;

a second pulley connected to a rear portion of the exercise deck; and

a perforated tread belt surrounding the first pulley and the second pulley and movable in a performance of an exercise;

a first display incorporated into the exercise deck, with the perforated tread belt surrounding at least one region of the first display, and with the first display being configured to be visible through the perforated tread belt as the perforated tread belt moves; and

a second display incorporated into the console;
wherein the first display and the second display are configured to have coordinated images depicted thereon.

14. The exercise device of claim 13, wherein the perforations in the perforated tread belt are filled with windows formed from a transparent material.

15. The exercise device of claim 14, wherein the windows are chemically bonded to the perforated tread belt.

16. The exercise device of claim 15, wherein the perforated tread belt is configured to direct loads away from the windows.

17. The exercise device of claim 14, wherein a thickness of the windows is less than a thickness of the perforated tread belt. 5

18. The exercise device of claim 17, wherein an engagement surface of the perforated tread belt is above outer surfaces of the windows.

19. The exercise device of claim 13, wherein the perforations in the perforated tread belt have a square shape, a 10 triangular shape, or an asymmetric shape, or combinations thereof.

20. The exercise device of claim 13, wherein each perforation in the perforated tread belt includes a perforation 15 edge formed between a wall of the perforation and an inner surface of the perforated tread belt, the perforation edge configured to wipe away substances obscuring a view of the first display.
